United States Patent Office.

ROBERT HENEAGE AND ALBERT STORER, OF BUFFALO, NEW YORK.

Letters Patent No. 94,205, dated August 31, 1869.

IMPROVEMENT IN MACHINE FOR ROUNDING THE CORNERS OF SLATE-FRAMES.

The Schedule referred to in these Letters Patent and making part of the same.

To all whom it may concern:

Be it known that we, ROBERT HENEAGE, and ALBERT STORER, both of Buffalo, in the county of Erie, and State of New York, have invented certain new and useful Improvements in Machines for Rounding the Corners of Slate Frames; and we do hereby declare that the following is a full and exact description thereof, reference being had to the accompanying drawings, making part of this specification, in which—

Figure 1 is a perspective view, and

Figure 2, a plan of the under side of the movable table, showing the slotted adjustable bars.

Like letters of reference indicate corresponding parts in both figures.

Our invention consists in arranging, on a bench, a movable table, which, by means of slotted bars and levers, presents the corner of a slate-frame, placed upon it, to the cutter, in such a manner as to round it, as hereinafter described.

In the drawings—

A represents a bench or operating table, on which is arranged the movable table B, one corner of it being cut away, the object to be presently explained.

On the under side of this table, (see fig. 2,) a long, slotted, metal bar, C, is sunk in, coming flush with the under surface of the table, and running transversely from one corner to the other, where it is pivoted at b to a short, slotted bar, D, the other end of which works on a pivot, e, set in it, and into the bench A.

These two bars, C and D, at their connection, b, with each other, form a kind of toggle-joint, which aids in giving the table B its peculiar motion.

The bar C is provided with slots, d d, and pins, e e, to allow the table to be adjusted forward, or to move it nearer to or further from the cutter, to make the diameter of the corner-cut less or greater, as desired.

The extreme end of this bar projects from the table, and has a long slot, a, through which a pin, f, is set, and fastened into the bench A. This allows the table to move forward and back, as well as serving as a pivot for table to swing to the right and left on.

The table B has a raised edge, g, formed on its outside, to set the slate E against.

An adjustable stop, h, is also set in the table, to adjust the slate forward or back to suit the size of the slate to be presented to the cutter.

This operating-table B is moved by a long hand-lever, F; resting on, and pivoted to, at one end, the bench A. A short connecting-arm or lever, G, is pivoted to this, and also to the table B.

The cutter H works on an upright shaft, i, suitably arranged on the operating-bench A, and is rotated by pulley j.

The corner of the table B is cut away next the cutter, so as to leave room for the play of the cutter, and also to allow the corner of the slate, when properly placed, to project over and come in contact with the cutter.

The operation and working of the machine are as follows:

The lever F is taken by the operator's left hand and drawn toward him, bringing the edge, k, of the table B, close to the lever-edge, as shown in fig. 1. This brings the upper corner of the slate-frame next to the revolving cutter.

The operator holds down the slate with his right hand, and pushes the lever F with his left hand from him, and, by the action of the short connecting-lever G, the toggle-connection b, of bars C and D, (on the under side of table B,) and the slot a and pin f, the table is drawn gradually inward up to a certain point, (the apex of the slate-corner,) when, by continued pushing of the lever F, it pulls it forward again till it reaches a stop, l, (the position shown in red lines,) the cutter meanwhile operating on the edge of the slate, and rounding it.

This operation is, of course, repeated on each of the four corners, and occupies but a few moments.

The whole device is of the simplest form and construction.

We are acquainted with a patent, No. 50,170, dated September 25, 1865, for "dressing edges of slate-frames," which shows a peculiar rocking or vibrating frame to hold the slate; we are also aware that there are various devices in which the cutter is made to describe the arc of a circle; such, however, are not the equivalents of our device.

What we claim as our invention, and desire to secure by Letters Patent, is—

The slotted bars C D, with their pivots b c f, table B, hand-lever F, and connecting-arm G, when the parts are constructed, arranged, and operated, substantially as described, and for the purpose specified.

In witness whereof, we have hereunto signed our names, in the presence of two subscribing witnesses.

ROBT. HENEAGE.
ALBERT STORER.
